SLIDEWAY FOR WHEEL CARRIAGES OF
GEAR-GRINDING MACHINESArthur Stephan, Chemnitz, Germany, assignor to
J. E. Reinecker Aktiengesellschaft, Chemnitz,
GermanyApplication September 21, 1937, Serial No. 164,869
In Germany September 26, 1936

2 Claims. (Cl. 51—166)

My invention relates to improvements in grinding machines of the type having a work table, on which the piece of work is fixed, a carriage carrying the grinding wheel, a frame supporting 5 said wheel carriage and having a guide track projecting therefrom, on which the wheel carriage is slidably and onesidely mounted in an overhanging position, and means for reciprocating the work table and wheel carriage relatively 10 to each other and in a direction rectangular to the sliding motion of the wheel carriage.

The improvements aimed at by this invention will be more fully understood by critically reviewing the state of the art, as known for instance 15 from United States Patent 1,650,422. In the latter a grinding machine is shown, the guide track of which slidably supporting the wheel carriage comprises two spaced track members, an upper and a lower one, presenting up and down- 20 wardly projecting flanges which are embraced and interengaged by corresponding guide flanges inwardly projecting from the wheel carriage.

It is common practice to provide wheel carriages slidably attached to guide tracks of the 25 design indicated with means for re-adjusting at least one of their guide flanges relatively to the guide track of the machine so as to secure always a close fit at the latter, namely to compensate for wear at the various guide and slide ways and 30 other faces frictionally engaging each other; more especially because torques rapidly changing in their direction are imparted to the overhanging wheel carriage during the grinding operation.

35 Said torques and impacts causing wear and friction in addition to that caused by the own weight of the overhanging wheel carriage and entailing eventually play at the interengaging surfaces render means for re-fitting and read- 40 justing the latter indispensable.

This is true, more especially with gear grinding machines since for high grade workmanship, as 45 for instance high speed precision gearings, motor gears, aero-engine gears etc. the grinding wheels of gear grinding machines have to be displaced relative to the workpiece at utmost small amounts (0.00005 inch) in order to eliminate the wear of the grinding wheels during operation, respectively for adjusting the grinding wheels to attain a certain thickness of the teeth of the work- 50 pieces etc. Therefore, one of the principal demands for said slide ways of gear grinding machines is the possibility of an easy and exact displacement of said wheel carriages.

55 It is, however, very difficult to meet these re-

quirements because the slide ways being arranged at the side of the wheel carriages are not only charged by weight of said wheel carriages but tilting moments and couples of forces are coming forward effecting in planes vertically to the lengthwise direction of the guideways. For this reason it has been necessary till now to support the wheel carriages of gear grinding machines with guideways arranged at the side thereof by aid of retaining members secured to the wheel 10 carriages by suitable means.

It is well known that retaining members very often cause disturbances when the operator removes the wheel carriages from the guideways for cleaning, greasing and so on because it is very difficult to re-adjust the retaining members with the same pressure as before, owing to the fact that re-adjustment has to be effected by hand. The wheel carriages of gear grinding machines can be displaced only for very small amounts and, therefore, the differences of pressure of the retaining members are of great disadvantage for the accuracy and sensibility of the displacement, especially because great temporal periods are lying between a plurality of 20 displacements so that the stiction (friction of rest) must be overcome when displacing.

The principal object of this invention is to provide slide ways for said horizontally sliding wheel carriages with guideways arranged at the side thereof, free from said disadvantages and moreover capable to carry the weight of the wheel carriages and to counteract as well tilting moments as couples of forces acting in planes vertically to the lengthwise direction of the guideways.

Another purpose of the invention is a permanent equal adjustment of the wheel carriages to the guideways independent of the ability of the operator. Furthermore errors which may arise from the plurality of elements will be reduced as 40 much as possible by this invention and retaining members need not be employed at all.

Other advantages and objects will be in part indicated in the following description and in part rendered apparent therefrom in connection with 45 the annexed drawing.

I attain these objects by an arrangement illustrated in the accompanying drawing, in which

Fig. 1 is a vertical section of the slide way with the frame and the wheel carriage.

Fig. 2 is a view of the wheel and the gear seen in direction of the arrow A.

The invention comprises a frame α and a wheel carriage β which is arranged in a sliding manner at the side of said frame α in horizontal di- 55

rection. The wheel carriage 2 carries pivotally mounted a grinding wheel 1 for grinding a work-piece 5 at the flanks 11, 12, 13 etc. of the teeth.

The wheel carriage 2 is to be displaced transversally (perpendicular) to the plane of the drawing. This displacement is effected by means of a feed screw 3 shown in Fig. 1 in vertical section and by means of a nut 4 fixed at the side of the wheel carriage 2, both the feed screw 3 and the nut 4 co-operating in a well known manner for slidingly displacing the wheel carriage.

According to this invention the frame *a* of the grinding machine is provided with two spaced guide-track members, an upper and a lower one, forwardly projecting from said frame; the upper track member is formed at its upper face with a recess of V-cross sectional shape open at the top and presenting two guideways 7, 8—hereinafter called a primary and a secondary guide way respectively.

Guideway 7 is slightly inclined towards the horizontal plane while the other guideway 8 is considerably more inclined towards the same, both guideways 7 and 8 carrying the weight of the wheel carriage 2, the latter is formed at its upper section with a downwardly projecting flange of corresponding cross sectional shape for engagement with said V-shaped guide ways 7 and 8. The wheel carriage 2 being arranged at the side of the frame *a* causes besides the pressure in vertical direction a tilting moment about the guideways 7 and 8 as an axis.

The principal object of this invention, namely, to avoid the use of any screwed retaining member, which always may cause disturbances, is attained by the arrangement of two additional, substantially vertically disposed guide ways, namely a third one designated 9 and a fourth one designated 10.

Guideway 9 is formed at the frame *a* proper above the upper track member and extends substantially parallel thereto for cooperation with a corresponding guide face, which is provided according to this invention at an extension upwardly projecting from the upper portion of the wheel carriage, while guideway 10 is arranged at the front face of the lower track member in substantially vertical disposition and for cooperation with a corresponding guide face provided at the rear of the lower end of the wheel carriage.

By virtue of said guide ways 9 and 10 and their specific disposition above and below the V-shaped recess 7, 8 of the upper guide track member, the wheel carriage 2 can be easily mounted and dismounted by simple putting in and out of the same after having removed the feed screw 3 and without unscrewing any retaining member.

The plane of the guideway 8 is inclined towards the parallel planes of the guideways 9 and 10 thus forming the angle α . The latter is very small generally not larger than 10 degrees. The object of this arrangement is to create very favorable

conditions for counteracting the tilting forces. In practice even a much larger torque than that produced by the weight of the wheel carriage 2 can be effective in the direction 6 without the danger of the wheel carriage 2 jumping out of the guideways 7 and 8.

Having thus revealed this invention, I claim as new and desire to secure the following combinations and elements, for equivalents thereof, by Letters Patent of the United States:

1. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

2. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

3. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

4. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

5. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

6. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

7. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

8. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

9. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

10. In a grinding machine having a frame and a grinding wheel carriage slidably supported in onesided overhanging position by said frame, the combination with two spaced track members, an upper and a lower one, projecting from said frame, the upper track member being formed at the top with a recess of V-cross-sectional shape presenting two inclined guide ways, a primary and a secondary one, of a guide flange of corresponding cross sectional shape formed at the rear of the wheel carriage and downwardly projecting therefrom for engagement with said primary and secondary guide ways, a substantially vertically disposed third guide way formed at the frame proper above said upper track member and extending parallel thereto, an extension upwardly projecting from the wheel carriage and presenting a guide face for cooperation with said third guide way, a substantially vertically disposed fourth guide way formed at the front of said lower track member, and another guide face provided at the lower end of the wheel carriage for cooperation with said fourth guide way.

ARTHUR STEPHAN.
